LAMP BELL FOR GLOBES AND SHADES

Filed April 20, 1926

Patented Nov. 23, 1926.

1,608,354

UNITED STATES PATENT OFFICE.

JACOB B. BANDER, OF NEW YORK, N. Y.

LAMP BELL FOR GLOBES AND SHADES.

Application filed April 20, 1926. Serial No. 103,323.

This invention relates to lamp bells such as are used in supporting hanging globes and shades for electric lights and the like.

In devices of this character it is quite common to provide a shank or stem whereon is mounted a bell proper within which are provided globe supporting fingers, the rim or neck of the globe being grasped between these fingers and the edge or rim of the bell, the fingers supporting the weight while the bell rim holds the globe from slipping. Owing to inequalities in the thickness of the globe neck and imperfections in the formation of the bell and fingers an equal grip of the fingers on the globe is frequently not obtainable with the ordinary construction.

One important object of the invention is to so improve the general construction of devices of this kind that the fingers will grip the globe equally under all the usual variations found in thickness and shape of the several parts.

A second important object of the invention is to provide improved means, in such devices, for rockingly supporting the fingers, a third important object of the invention is to provide an improved globe support having a bell slidably mounted on the supporting shank to move into and out of cooperative relation with certain tilting fingers so that the globe may be readily placed on or removed from the device.

With the above and other objects in view as will be hereinafter apparent, the invention consists in general of certain novel details of construction and combinations of parts hereinafter fully described, illustrated in the accompanying drawings and specifically claimed.

40 In the accompanying drawings like characters of reference indicate like parts in the several views, and:

Figure 1 is a vertical diametrical section through the invention.

45 Figure 2 is a detail section on the line 2-2 of Figure 1.

Figure 3 is a section on the line 3-3 of Figure 2.

50 Figure 4 is a detail section on the line 4-4 of Figure 1.

Figure 5 is a detail end view of a bell clamping screw used herewith.

Figure 6 is a detail view of a modified hanger.

55 In the embodiment of the invention herein disclosed there is employed a tubular shank

or stem 10 having secured to its lower end a lamp socket 11 of ordinary construction. Above the socket 11 the stem passes through an elongated opening 12 formed in the horizontal portion 13 of a finger bar having downwardly and divergently extending arms 14 terminating at their lower ends with vertical portions from which extend globe gripping fingers 15. The horizontal portion 13 rests on a cross bar 16 which extends diametrically through the stem and lies transversely of the finger bar, being provided at its ends with rebent portions 17 gripping the edges of the finger bar so that the latter is, 70 in effect, pivoted to the stem.

Slidable and rotatable on the stem 10 is a sleeve having a threaded body 18 provided at its lower end with a hexagonal head or flange 19 for engagement by a wrench 75 or the like. On this sleeve is screwed a lock nut 20 and on top of this lock nut rests the central part of a bell 21 of suitable ornamental form and preferably made from stamped or spun metal, a suitable opening 80 being provided for the passage of the stem 10. The lower edge of this bell is in the form of a depending skirt 22 provided with head 23 and the fingers 15 extend outwardly somewhat beyond the bead so that the globe, 85 the neck of which is indicated at G in dotted lines, may be grasped between the bead 23 and fingers 15. At the upper part this bell is provided with ventilating openings 24 and on top of the bell rests a cap 25 having 90 an internally channeled edge 26 spaced from the bell and covering the openings 24, the spacing of the channel permitting escape of the air which may enter the channel through the openings 24. To hold the cap 95 and bell firmly in position a suitable nut 27, having an internal flange 28 at its upper end, is screwed on the threaded sleeve 18 until the flange 28, fitting closely on the stem, engages the end of the sleeve whereupon the nut 20 is adjusted to clamp said cap and bell against the lower end of the nut 27. Both the sleeve 18 and flange 28 are provided internally with grooves 29 100 aligned with each other upon the nut 27 being properly positioned. On the stem 10 is a pair of vertically spaced studs 30 and 31, the lower stud 30 engaging the flange 28 when the bell is in globe engaging position. These studs are of such size as to pass 105 through the grooves 29 upon the latter being brought into vertical alignment with

a stud and thus by so positioning the grooves the bell may be raised until it is above the upper stud 31 whereupon it may be rotated to disalign the upper stud and grooves so that it will be supported in raised position.

It will be obvious that, with the bell raised the globe may be placed in position by first inserting one arm of the finger bar through the opening in the top to a considerable extent and then moving the globe until the other finger passes through the opening. The globe is then straightened and centered on the fingers after which the bell is moved to lowered position, the fingers tilting on the bar 16 to give an equal grip for each finger.

As a means of suspending the device a cap 32 having a ring 33 may be screwed on top of the stem 10. A modified form permitting the sleeve to pass off the stem is shown in Figure 6.

There has thus been provided a simple and efficient device of the kind described and for the purpose specified.

25 It is obvious that minor changes may be made in the form and construction of the invention without departing from the material spirit thereof. It is not, therefore, desired to confine the invention to the exact 30 form herein shown and described, but it is desired to include all such as properly come within the scope claimed.

Having thus described the invention, what is claimed as new, is:

26 1. A lamp shade support including a vertical stem, a cross bar extending diametrically of the stem, and a finger bar having a centrally disposed elongated opening through which the stem passes, said finger bar resting on the cross bar with the latter extending transversely of the finger bar, the said finger bar being fixed to the cross bar for transverse tilting therewith.

2. A lamp shade support including a vertical stem, a cross bar extending diametrically of the stem, and a finger bar having a centrally disposed elongated opening through which the stem passes, said finger bar resting on the cross bar with the latter extending transversely of the finger bar, said cross bar having rebent end portions gripping the edges of the finger bar and extending over the top thereof to prevent disengagement of the finger bar from the cross bar, the said finger bar being tiltable transversely of the cross bar.

3. A lamp shade support including a vertical stem, a finger bar having a central portion provided with an opening through which the stem passes, said opening being larger than the stem to permit tilting movement of the finger bar on the stem, said finger bar having a plurality of arms extending outwardly from the central portion and provided with terminal shade engaging

portions engageable under the neck portion of a shade, and a bell slidable on the stem independently of the finger bar and engageable on the neck portion of such shade.

4. A lamp shade support including a stem, 70 and a finger bar extending on opposite sides of said stem and having pivotal connection centrally of the bar with said stem; in combination with a bell slidable vertically on the stem between lowered shade engaging and raised shade freeing positions, and means to releasably hold the bell in each of said positions.

5. A lamp shade support including a vertical stem, a cross bar extending diametrically of the stem, and a finger bar having a centrally disposed elongated opening through which the stem passes, said finger bar resting on the cross bar with the latter extending transversely of the finger bar; in combination with a bell slidable vertically on the stem between lowered shade engaging and raised shade freeing positions, and means to releasably hold the bell in each of said positions.

6. A lamp shade support including a vertical stem, a cross bar extending diametrically of the stem, and a finger bar having a centrally disposed elongated opening through which the stem passes, said finger bar resting on the cross bar with the latter extending transversely the finger bar, said cross bar having rebent end portions gripping the edges of the finger bar; in combination with a bell slidable vertically on the stem between lowered shade engaging and raised shade freeing positions, and means to releasably hold the bell in each of said positions.

7. A lamp shade support including a vertical stem, a finger bar having a central portion provided with an opening through which the stem passes, said opening being larger than the stem to permit tilting movement of the finger bar on the stem, said finger bar having a plurality of arms extending outwardly from the central portion and provided with terminal shade engaging portions engageable under the neck portion of a shade; in combination with a bell slidable vertically on the stem between lowered shade engaging and raised shade freeing positions, and means to releasably hold the bell in each of said positions.

8. A lamp shade support including a stem, and a finger bar extending on opposite sides of said stem and having pivotal connection centrally of the bar with said stem; in combination with a sleeve slidably and rotatably mounted on the stem and having an internal groove extending from end to end, a bell carried by the sleeve and having a rim portion cooperating with the finger to form shade gripping means, and a pair of spaced studs projecting from the stem and adapted

to pass through the groove in the sleeve upon said groove being alined with the respective stud, one of said studs engaging above the sleeve upon the latter being

5 lowered and the other stud engaging beneath the sleeve upon the latter being raised.

9. A lamp shade support including a vertical stem, a finger bar having a central portion provided with an opening through 10 which the stem passes, said opening being larger than the stem to permit tilting movement of the finger bar on the stem, said finger bar having a plurality of arms extending outwardly from the central portion 15 and provided with terminal shade engaging portions engageable under the neck portion

of a shade; in combination with a sleeve slidably and rotatably mounted on the stem and having an internal groove extending from end to end, a bell carried by the sleeve 20 and having a rim portion cooperating with the finger to form shade gripping means, and a pair of spaced studs projecting from the stem and adapted to pass through the groove in the sleeve upon said groove being 25 alined with the respective stud, one of said studs engaging above the sleeve upon the latter being lowered and the other stud engaging beneath the sleeve upon the latter 30 being raised.

In testimony whereof I affix my signature.

JACOB B. BANDER.
